(57) **CLAIM**

I claim, the ornamental design for a film-dispensing cassette for garbage, as shown and described.

DESCRIPTION

FIG. 1 is a bottom perspective view of film-dispensing cassette for garbage showing our new design;

FIG. 2 is a side elevation view thereof, the opposite and adjacent sides being mirror images thereof;

FIG. 3 is a sectional view thereof, taken along the line 3-3 of FIG. 2;

FIG. 4 is a bottom plan view thereof; and,

FIG. 5 is a top plan view thereof.

The broken-line disclosure represents unclaimed portions of the cassette, and a broken-line abutting a claimed surface which is shown with surface shading is understood the represent an unclaimed boundary between claimed and unclaimed surfaces.
